UNITED STATES PATENT OFFICE.

STERLING H. CAMPBELL, OF ST. LOUIS, MISSOURI.

COUPLER-RELEASE RIGGING.

Application filed September 23, 1922. Serial No. 590,062.

To all whom it may concern:

Be it known that I, STERLING H. CAMPBELL, a citizen of the United States of America, residing at the city of St. Louis, State of Missouri, United States of America, have invented a certain new and useful Coupler-Release Rigging, of which the following is such a full, clear, and exact description as will enable anyone skilled in the art to which it appertains to make and use the same, reference being had to the accompanying drawings, forming part of this specification.

My invention relates to a coupler release rigging and particularly to that type of rigging in which the actuating rod rotates to lift the pin and in which the arm or equivalent operating portion of the rod moves in unison with the locking pin.

The object of my invention is to so construct a release rigging of the class described so that the handle, by means of which the actuating rod is controlled, may return to normal position, while the coupler pin is in raised or unlocked position.

In the accompanying drawings which illustrate some forms of coupler release rigging made in accordance with my invention, Figure 1 is top plan view of a portion of a railway car to which one form of my device is applied. Figure 2 is an end view, Figure 3 is a front view, Figure 4 is a plan view showing a modification, Figure 5 is an enlarged section on the line 5—5 of Figure 4, Figure 6 is an end view of the handle, Figure 7 is a front view of the handle, Figure 8 is a plan view showing a further modification, Figure 9 is an end view of the form shown in Figure 8, Figure 10 is a plan view of a further modification, Figure 11 is a section taken on the line 11—11 of Figure 10. Figure 12 is an end view of the handle shown in Figure 10. Figure 13 is a plan view showing a still further modification, Figure 14 is an end view of the parts shown in Figure 13 and Figure 15 is a front view of the connecting link shown in Figures 13 and 14.

1 indicates a railway car carrying a coupler head 2 resiliently mounted in any usual manner in the striking block 3 and provided with a lock pin 4 by means of which its knuckle is controlled. Referring first to Figures 1, 2 and 3, 6 is the actuating rod or rock shaft rotatably mounted in brackets 7 secured to the end of the car. The rod 6 is provided with a forwardly projecting arm

8 having a lateral extension 9, preferably provided with a turned over end or hook 10. The extension 9 passes through an eye 12 carried on the lock pin 4 and elongated to 60 extend in the direction of the length of the car. This construction allows the operating arm and lock pin to have relative movement both laterally and longitudinally in a horizontal plane, but enforces their movement in unison vertically. In order that the handle 13 may not project into the space between the cars when the lock pin is in raised position, I provide the end of the rod 6 with a short crank arm 14 to which the handle 13 70 is pivoted at 15 so that the handle may drop down into normal or vertical position, as best shown in Figure 2, while the pin remains raised.

In Figures 4 to 7 I have shown a modified form of device in which the operating arm 8 is replaced by an arm comprising a downwardly and forwardly projecting part 16 and a part 17 extending parallel with the upper face of the coupler when the pin is 80 in lowered or locked position. In this construction, the hook 10 is formed on the end of the part 17 and the said part extends through an eye 18 carried on the pin 4 and elongated like the eye 12 but extending in a 85 transverse direction instead of longitudinally. This construction, like that above described, allows the relative movement of the arm and lock pin in a horizontal plane but compels their movement in unison vertically. In the present instance, however, the lateral movement is allowed by the arm moving in the direction of the length of the eye and the longitudinal movement by the eye moving in the direction of the length of the 90 arm which is the reverse of the former construction. In this construction, I have shown the handle 13 pivoted to a casting 19 placed over the crank arm 14 and held in position by a bolt 20. I have also shown 100 the cast brackets 7 replaced by brackets 21 formed of sheet metal and having bearings 22 struck up from the metal.

In Figures 8 and 9 I have shown a modification in which the actuating rod 6 is carried in a single bracket 23 provided with a tapering passage 24 to allow the outer end of the rod to move in a horizontal plane to accommodate the longitudinal movement of the coupler head. In this construction, the end of the rod 6 passes directly through an eye 25 of the usual form on the pin 4,

The end of the rod 6, while not distinct from the body of the rod, forms in effect an operating arm functioning in a manner similar to the operating arm hereinbefore described. I have also shown the crank arm 14 flattened and provided with a turned over portion 26 forming a stop for the handle 13, thus obviating the necessity of bifurcating the end of the handle as shown 10 in Figures 1 and 3.

In Figures 10, 11 and 12 the rod 6 is similar in form to that shown in Figure 1 but the use of the elongated eye 12 is obviated by the use of an inner bracket 27 15 slotted to allow the rod to move toward and away from the car. The handle 13 is provided with an aperture 28 to pass around the rod and with a stop 29 to contact with the crank arm 14. A pin 30 holds 20 the handle in place.

In Figures 13, 14 and 15 the end of the arm 8 is connected with the lock pin by a link 31 pivoted to the said arm at 32 and provided at its lower end with an elongated 25 loop 33 engaging with the eye of the lock pin. The elongated form of the loop 33 allows for the lateral movement of the coupler while the pivot joint 32 compensates for the longitudinal movement. As in 30 the other forms described, however, the arm and lock pin can move only in unison in a vertical direction. The handle in this construction, as in that last described, passes around the rod 6. The crank arm 14 is, 35 however, not used, the handle being provided with a stop 34 and the rod with a pin 35, serving both to cooperate with the stop and to hold the handle in position.

Having fully described my invention 40 what I claim as new and desire to secure by Letters Patent of the United States is:

1. In a device of the class described, the combination, with a coupler head having a

lock pin of an actuating rod rotatably mounted, an operating arm carried by said rod, said arm and lock pin operatively connected to have relative movement both longitudinally and laterally in a horizontal plane, but to move in unison vertically and a handle for said actuating rod having 50 movement relative thereto, whereby said handle may return to normal position when the lock pin is in raised position.

2. In a device of the class described, the combination with a coupler-head provided 55 with a lock-pin having an elongated eye, of a rock-shaft, an operating arm carried by said shaft and extending through said eye, whereby said arm and pin move vertically in unison but are capable of relative lateral 60 and longitudinal movement, and a handle for actuating said shaft, said handle being capable of movement relative to said shaft, whereby the handle may return to normal position while the lock-pin is in raised position.

3. In a device of the class described, the combination with a coupler-head provided 70 with a lock-pin having an eye elongated in the direction of the length of the coupler-head, of a rock-shaft an arm carried by said rock-shaft and extending through said eye, whereby said arm and eye move vertically in unison but are capable of relative longitudinal movement resulting from the shape 75 of the eye and relative lateral movement due to the movement of the arm through the eye, and a handle for actuating said shaft, said shaft being capable of movement relative to said shaft whereby the handle 80 may return to normal position while said pin is in raised position.

In testimony whereof, I have hereunto set my hand and affixed my seal.

STERLING H. CAMPBELL. [L. S.]
